C. W. JOHNSON.

FIRE ESCAPE.

APPLICATION FILED MAR. 15, 1915.

1,230,169.

Patented June 19, 1917.

UNITED STATES PATENT OFFICE.

CHARLES W. JOHNSON, OF ORANGE, MASSACHUSETTS.

FIRE-ESCAPE.

1,230,169.

Specification of Letters Patent. Patented June 19, 1917.

Application filed March 15, 1915. Serial No. 14,440.

To all whom it may concern:

Be it known that I, CHARLES W. JOHNSON, citizen of the United States, residing at Orange, in the county of Franklin and State of Massachusetts, have invented certain new and useful Improvements in Fire-Escapes, of which the following is a specification.

My invention relates to lowering devices, and has particular reference to a fire escape which has for its primary object the provision of a friction block having apertures, through which a rope or the like is reeved for movement, and is particularly adapted for lowering persons and the like from the upper stories of a burning building.

The primary object of my invention is to provide a device of this character which is simple in construction, cheap to manufacture, and one which is effective in operation.

A further object of my invention contemplates the provision of a friction block having a plurality of alternately arranged apertures therein, the said block also having grooves communicating with said apertures, said apertures and grooves being adapted to receive a rope or a similar flexible supporting element by which a person may be supported and conveyed slowly by gravity to the earth from a height.

A still further object of my invention resides in providing a novel means for supporting a body in connection with the conveying element.

A still further object of my invention resides in the provision of depressions or grooves in the opposite faces of the block communicating alternately with the various apertures for the reception, guidance and frictional engagement of a rope or other flexible element.

With the above and other objects in view my invention resides preferably in the construction, combination, and arrangement of parts as hereinafter set forth in the specification and illustrated in the accompanying drawings, in which—

Figure 1 is a perspective view showing the use of my invention.

Fig. 2 is a front elevation of the same showing the peculiar arrangement of the conveying element and the supporting loop associated therewith.

Fig. 3 is a transverse sectional view of a portion of one of the supporting loops.

Fig. 4 is a plan view of the friction block.

Fig. 5 is a transverse sectional view on the line 5—5 of Fig. 2 looking in the direction of the arrow, and

Fig. 6 is a detail sectional view of a portion of the device.

Similar reference characters indicate similar parts throughout the various views of the drawings.

Referring more particularly to the drawings in which the preferred embodiment of my invention is illustrated, I have provided a friction block 1 having a supporting loop 2 laterally extending therefrom and provided with an eye 3 for supporting the friction block 1 at any desired point. The opposite extremities of the block 1 are turned down as indicated at 4 and 5 for a purpose which will hereinafter be set forth.

It is to be understood that my invention may be used for various purposes, but I find it most advantageous in use as a fire escape for lowering persons and objects from a burning building. The block 1 is provided with a plurality of apertures 6, the said apertures 6 being arranged in staggered relation or *en echelon* in the block 1, certain of said apertures being in communication with certain others of said apertures by means of grooves or depressions 7 formed in the opposite faces of the block 1. The turned down portions 4 and 5 are each provided with a guiding aperture 8 as shown in Figs. 2 and 6. The guiding apertures in each of the said turned down portions 4 and 5 are similar, the only difference being that the two apertures 8 emerge at opposite sides of the block, as indicated in Fig. 2, these emerging ends of the apertures 8 being disposed at right angles thereto. A rope when reeved through all of the apertures, will have its end portions emerging from the block in substantially parallel lines. A rope or similar flexible element, indicated generally by the numeral 9, when reeved through the apertures 6 and the openings 8 of the ends 4 and 5, as above stated

will have intermediate portions 10 thereof disposed within the grooves 7. The rope at the points at which it is in engagement with the block, is snugly in contact therewith at all times so as to afford frictional retention therein. As shown to advantage in Fig. 5, the respective ends of the apertures 6 are rounded or beveled as indicated at 11 so as to facilitate passage of the rope therethrough and to prevent mutilation or break-

ing thereof. While a limited number of apertures have been shown, it will be understood that any desired number of these apertures may be provided, it being noted 5 that the intermediate portions 10 of the rope 9 are always in frictional engagement with the block 1, thus affording ample friction to prevent excessive speed of a descending body when the device is in use.

10 In Fig. 1 the manner of applying the invention is disclosed, and it will be noted that the opposite extremities of the rope or the line 9 are provided with holding loops 12, the said loops 12 being similar in construction and I will therefore describe but one of them. For this description attention is directed to Figs. 2 and 3 wherein the loop is shown on an enlarged scale. It will be noted that the loop includes a strap 13 of 15 flexible material having one extremity 17 thereof secured at 14 to a bight 15 formed in one extremity of the rope 9. The opposite extremity of the strap 13 is provided with a loop 16 through which the extremity 20 25 17 of the strap 13 passes. In order to apply the device to a body the loop 12 is enlarged to the required diameter and placed over the head of the user and passed down until the same is received approximately under the 30 arm pits as shown to advantage in Fig. 1 and indicated therein at 18. The manner of placing the device in position is shown at 35 19 at the upper figure in Fig. 1. In this portion of the view the building is indicated generally by the numeral 20, one of the walls thereof carrying a supporting hook 21 upon which the block 1 is mounted.

It is thought that the construction, uses, and advantages of my invention may be 40 readily gathered from the above description taken in connection with the accompanying drawing, and it will be noted that it is only necessary to place the loop formed by the strap 13, over the head as indicated 45 in the upper portion of Fig. 1 and under the arms of the user and then step from the window or from the point at which the person may be located. The block 1 will by

virtue of the engagement of the rope 9 with the openings 6 and grooves 7 allow the person to slowly descend. The opposite extremity of the rope will ascend as the load descends so that when the ground is reached the opposite extremity of the rope carrying the other supporting strap will be raised 55 into position for use of persons which may be following. It will be seen that this device is simple in construction, and one by which the provision of costly structures now in vogue is obviated and it will be also noted 60 that the scope of its uses is unlimited.

While I have shown and described my invention as possessing a peculiar form and construction, it is desired that it be understood that I may make such changes in the 65 details thereof that do not depart from the spirit and scope of the invention as claimed.

Having thus described my invention what I claim and desire to secure by Letters Patent is:

1. A friction block having a support securing means midway on its length, and having a series of transverse apertures disposed *en echelon*, said apertures being communicant by grooves arranged alternately at 75 opposite sides of the block said block having end apertures disposed at right angles to the transverse apertures.

2. A friction block having a support securing means midway of its length, and 80 having a series of transverse apertures spaced from each other both longitudinally and laterally of the block, and end apertures entering upon the side face of the block 85 extending out of a common edge face at right angles to the face at which they enter the block whereby a rope reeved through all of the apertures will have its end portions emerge therefrom in substantially parallel lines.

In testimony whereof I affix my signature in presence of two witnesses.

CHARLES W. JOHNSON.

Witnesses:

FRED B. HOWES,
EMIL GUSTAFSON.
